ARTHUR ALBERT PANNIER, OF SALT LAKE CITY, UTAH.

COMBINED HAND AND SELF-INKING STAMP.

1,401,436.

Specification of Letters Patent. Patented Dec. 27, 1921.

Application filed July 12, 1921. Serial No. 484,023.

To all whom it may concern:

Be it known that I, ARTHUR A. PANNIER, a citizen of the United States, residing at Salt Lake City, in the county of Salt Lake 5 and State of Utah, have invented a new and useful Combined Hand and Self-Inking Stamp, of which the following is a specification.

This invention relates to tumbler or self-10 inking hand stamps, and is more particularly directed to a device in which independent dies are employed, and in which each die is treated with an ink distinctive in color in order that when the several dies are simultaneously stamped upon material suitable 15 for the purpose, the resulting printed matter from each die will stand out more conspicuously.

In self-inking hand stamps in which the 20 inking pad is secured within the plunger-holding frame and in which a reversible die is adapted to be automatically inked when the operating handle, after being depressed, is released, it is possible, by means of a removable or fixed die plate provided with an 25 opening through which the reversible die is adapted to project, to print matter which contains several colors by supplying the pad which inks the removable or fixed die plate 30 with an ink of a different color from that supplied to the reversible die.

As in most cases of hand dating stamps, the device is so constructed that the dies which print the dates comprising the days, 35 months, and years, are fixed upon endless bands and are adapted to be shifted independently of each other in order that it may be possible to select any combination of day, month, and year and aline the several selected dies for impressing the same upon a letter. In order to make the date more conspicuous, the inking pad which the die just described is adapted to normally engage, is supplied with one kind of ink. A die plate 40 45 removably or rigidly mounted on the tumbler frame and provided with a central opening through which the date die is adapted to be projected, is inked by a pad containing ink of a different color from that supplied to the inking pad for the reversible die.

Furthermore it is advisable to hold the operating handle or plunger in an elevated po-

sition while inking the removable or fixed die mounted on the end of the frame. I have therefore provided an automatic locking means by which this plunger is locked into an inoperative position when the said plunger has been retracted to its normal position by the usual means, since it may happen that in applying the removable or fixed die to an inking pad, too great a pressure may be exerted on the operating handle of the stamp when the reversible die will be plunged into the inked pad for the removable die and give one color to all the printed matter.

In alining the different dies which comprise the date and which are formed on endless bands, it is necessary to employ some means to prevent these independent dies from falling out of alinement. I therefore employ an alining means provided with a slot. The material of the slot, instead of being cut away, is punched outwardly so that the said material will curl upwardly from the slot and provide a pair of flanges which will bear against the alined dies. A spring is employed to automatically grip a catch on the plate as it projects through an opening in the reversible die frame. The spring also serves to exert a pressure upon the pivoted alining plate so that as the spring-pressed catch is released, the pivoted plate will spring outwardly and away from the alined dies when it is necessary to make changes in the dies.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawings:

Figure 1 is a vertical section of my improved hand stamp with the plunger in elevated position and the adjustable or movable dies in engagement with an inking pad secured to the inner upper end of the tumbler frame.

Fig. 2 is a vertical section of the same with the dies on the reversible frame forced downwardly by the depressed plunger and through the slot in a die plate removably mounted on the end of the frame.

Fig. 3 is a transverse section of the plunger along the line 3—3 of Fig. 1, showing the means for locking the plunger in elevated position.

Fig. 4 is a view in perspective of the removable die plate which is adapted to be mounted on the bottom of the frame.

Fig. 5 is a vertical section of a hand stamp showing a modification in which the die located on the reversible die frame is not adjustable.

Fig. 6 is a sectional view similar to the view shown in Fig. 5, but in which the plunger is depressed and the die of the reversible die frame is forced through an opening in the removable die plate.

Fig. 7 is a view in perspective of the removable die plate, disclosing the printing characters.

Fig. 8 is a plan view of a slotted plate which is adapted to aline the adjustable dies shown in Fig. 1 on the reversible die frame.

Fig. 9 is a view in perspective of the alining plate and the automatic locking means for said plate.

In the drawings, 1 designates the main frame of what is known as the "tumbler" form of hand stamp, and only such parts of the operating mechanism will be described as are necessary to give a clear understanding of my invention as applied to this form of stamp. The "tumbler" form of hand stamp comprises, as usual, a handle 2 for depressing the yoke 3, which is connected to the main frame 1, and is herein-after described as supporting the printing characters 4. Each side member of the frame 1 is provided with a straight slot 5 in which travels a lug 6 projecting at right angles from an arm formed on or rigidly connected with the end of the yoke 3, as shown in Figs. 1 and 2.

A transverse bar 7, mounted in the ends of the yoke 3 and passing through the reversible frame 8, is adapted to ride in a curved slot 9 formed in the sides of the main frame 1.

Referring more specifically to Fig. 1, a lug (not shown in the drawings) is secured on each of the sides of the main frame 1 and is adapted to coöperate with slots formed in arms that depend from the die frame 8. When the handle 2 is depressed, the ends of the rod 7 will operate in the curved slots 9, and the lugs which have been previously described, but not shown, will ride in their respective slots, causing the die frame 8 and the printing characters 4 to be reversed in the same manner.

In Figs. 1 and 2 there is shown a movable or adjustable die provided with printing characters 4 and it comprises a series of endless bands, each provided with a plurality of dies projecting outwardly from the bands and spaced from each other and carrying printing characters. These endless bands are movable or adjustable on a drum 16, and owing to their printing characters, different combinations of the characters may be formed for printing various dates. No claim is made for this feature.

Ordinarily the base member 17 is used as a die plate, but in this instance I prefer to use it as a base secured to the die frame 8, (Figs. 1, 8 and 9). The base member 17 carries a movable plate 18 pivoted to said member, a latch 19 and a spring 20 having a twofold function. The pivoted plate 18 is slotted centrally thereof at 21, the material at the edges of the slot being bent outwardly and providing the out-turned flanges 22 which are adapted to lie snugly against dies 23. The dies are projected through the slot 21 which prevents the several dies from getting out of alinement with each other when the proper characters have been selected for printing the date. (Figs. 1 and 2).

A lug 24, secured to the plate 18 and projecting inwardly, toward the base plate 17, has an annular groove 25 which coöperates with the latch 19 to hold the alining plate 18 against the base member 17 when the said plate 18 is forced down upon the base. The base 17 is provided with an opening alining with an opening 27 in the latch 19 through which the lug 24 projects, but the portion 26 of the spring 20 is adapted to shift the latch 19 to such a position that the openings in the base 17 and the latch 19 are always slightly out of alinement. When the lug 24 is forced through the circular opening in the base 17, it will, by reason of its conical head, slide the latch 19 upon the base sufficiently to permit the conical head of the lug to pass through both openings. A portion of the catch surrounding the opening 27 in the latch 19 will slip into the annular groove 25 of the lug 24 and hold the plate 18 upon the base 17, since the spring 26 continually maintains the latch 19 in engagement with the lug 24.

When the plate 18 is thus secured to the base member 17, the other end of the spring 28, by means of the inturned portion 29, will press against the plate 18 and tend to force it outwardly. As the latch 19 is moved in opposition to the spring 26 and a portion of the edge of the opening 27 is released from the groove 25 of the lug 24, the pressure of the spring 28 will force the plate 18 outwardly and release it from its position of alining the dies 23.

On the end of the main frame 1 is removably mounted a relatively fixed die plate 30 provided with the die 31 having printing characters, a centrally located opening 32, the open hinge members 33 for pivotally mounting the plate 30 on a bar 34 secured to the frame 1, and a catch 35 which is adapted to snap over a bar 36 located on the frame 1 opposite to the bar 34 and to resiliently hold 10 the die plate 30 on the end of the tumbler frame 1.

An inking pad 37 is secured face downward in the upper portion of the main frame 1 and is adapted to be engaged by the dies 15 23, when the die frame and handle are normally in their elevated position where they are held by a spring 38 (Figs. 1 and 2).

Referring to Figs. 1, 2 and 3, a disk 39, centrally perforated at 40, through which 20 the plunger 41 is adapted to be reciprocated, is resiliently held against the plunger 41 by means of a spring 42 so that the edge 43 of the perforation 40 will slide into a groove 44 in the plunger 41 and hold the handle locked 25 in elevated position. A set screw 45, secured to the yoke 3 and adapted to ride in a slot 46 in the disk 39, limits the movement of said disk. By this construction an automatic locking means is provided to hold the 30 plunger inoperative when the plunger is in its normal position.

In Figs. 5 and 6 is shown a simpler form of device in which the printing characters are formed on a flat plate and are not adjustable, as shown in Figs. 1 and 2. The die plate 15 is reversible, and as shown, is adapted to invert the dies on the downward stroke of the handle 2.

The pivoted members 10 are provided with 40 a curved slot 11 in which the cross bar 7 is also adapted to ride, coöperating with a lug 12 which rides in a slot 13 formed in depending arms 14 carried by the die plate 15 to reverse the said die plate as the handle

45 2 is depressed. In this form the device shown in Figs. 8 and 9 is not employed, but with this exception, the same elements are present in both forms and the same reference characters are applied to corresponding parts 50 in all the figures, except that I have marked the printing characters 23^a in Figs. 5 and 6. The locking means employed for locking the handle 2 in Figs. 1 and 2, may also be applied to the construction shown in Figs. 5 and 6.

55 The importance of this device resides in the fact that the die 4 is adapted to be inked by the pad 37 in both forms with one kind of ink, while the die 31 may be applied to an inking pad having a different color of ink, so that when the handle 2 is depressed, the character 4 which has been furnished with an ink of a certain color will be released from the pad 37, projected downwardly and at the same time inverted so that it will 60 extend through the slot 32 in the die plate 30

and impress the material with printing characters simultaneously with the die plate 30, thus providing a stamping in two colors.

The operation of my device is as follows:

As shown in Figs. 1 and 5, the reversible die plate 15 is in normal position with the printing characters 23 and 23^a engaging the inking pad 37. The handle 2, yoke 3, and the plunger 41 are in normal elevated position. In Fig. 1 the plunger 41 is locked in 70 elevated position by the spring-pressed disk 39 but may be released by lateral pressure of the thumb. The printing characters 31 of the die plate 30 in Figs. 1 or 5 are first impressed upon an inking pad which is provided with an ink of a different color from that supplied to the pad 37. As the hand stamp is impressed upon material the locking means or disk 39 is shifted laterally in 80 order to move the catch 43 from the slot 44. When the plunger 41 is released and the handle 2 in either Fig. 1 or 5 is depressed, then the reversible die 23 or 23^a will be forced 85 downwardly and inverted and be impressed upon material, as the reversible printing dies 90 are inserted through the slot 32 of the movable die plate 30.

It will be seen that the dies 23 or 23^a, which may in this instance designate the date, will be provided with an ink of one color, while 95 the dies 31 will be provided with an ink of another color so that as the stamp is impressed, the date will appear more conspicuously than otherwise by reason of the fact that it is provided with a different color 100 from the other printed matter. When the handle 2 is released, the dies 23 and 23^a will be returned to their normal positions and engage the inking pad 37 preparatory to another stamping. It will always be necessary 105 to apply the die 31 manually to its inking pad, and it should precede the operation of the reversible dies carrying the other data to be stamped.

I have shown my invention applied to 110 hand stamps of the self-inking type, of which two forms are shown. This invention is, however, capable of wider application, for I consider that I am the first to combine a self-inking stamp with an ordinary hand stamp, the latter having an opening or space in its printing face through which the printing characters of the self-inking stamp are caused to project, whereby two stamped impressions may be simultaneously made in 115 contrasting colors. That part of my invention consisting of the die plate 30 may be applied to any make of self-inking stamp.

Moreover, these elements are combined to 120 permit the use of the stamp as a self-inking stamp, a hand stamp or a combination self-inking and hand stamp, this result being effected by the use of the automatic locking device disclosed in Fig. 3 of the drawing. By the removal of the die plate 30, other 125

130

plates having different printing matter may be substituted therefor. In this way a great variety of changes may be made in the device which would ordinarily require a number of different stamps to produce. While it is preferred that the die plate 30 be interchangeable, I wish it understood that a permanently fixed die plate would embrace my invention.

10 Having thus described my invention, I claim:

1. In a hand stamp, the combination of a main frame, a plunger slidably mounted relative thereto, a reversible die rotatably mounted on the plunger, and means for supporting a die in advance of the reversible die, said means providing for a substantially simultaneous impression of both dies with one impression surrounding the other.

20 2. In a hand stamp, the combination of a frame, a plunger slidably mounted relative thereto, a reversible die frame rotatably mounted on the plunger and provided with a die, and a plate provided with a die positioned in advance of the die frame and having an opening through which the die of the reversible die frame is adapted to project.

30 3. In a hand stamp, the combination of a frame, a plunger slidably mounted relative thereto, a reversible die frame provided with a plurality of adjustable dies, means for alining the several dies, a die plate positioned in advance of the die frame and provided with an opening, the said alined dies being adapted to be projected through the opening in the die plate.

40 4. In a hand stamp, the combination of a frame, a die plate removably mounted on the end of the frame and provided with an opening, a plunger slidably mounted on said frame, a reversible die frame rotatably mounted on the plunger and provided with a die, the reversible die frame being adapted to project its die through the opening in the removably mounted die plate.

45 5. In a hand stamp, the combination of a frame, a plunger slidably mounted thereon, a reversible die frame rotatably mounted on the plunger and provided with a die, an inking pad, and a die plate provided with an opening and positioned in advance of the die frame, said reversible frame being adapted to project the die located thereon through the opening in the die plate when the plunger is depressed and to cause the die to engage the inking pad when the plunger is released.

60 6. In a hand stamp, the combination of a frame, a plunger slidably mounted thereon, a reversible die plate rotatably mounted on the plunger, an inking pad secured to the frame, a die plate provided with an opening and positioned in advance of the reversible die plate, said reversible die plate being adapted to be projected through the opening

in the other die plate, said reversible die plate being adapted to normally engage the inking pad, and means for locking the reversible die plate in its normal position of engagement with the inking pad.

7. In a hand stamp, the combination of a frame, a plunger slidably mounted thereon, a reversible die plate rotatably mounted on the plunger, a die plate provided with an opening and removably mounted on the end of the frame, said reversible die plate being adapted to be projected through the opening in the horizontal plane of the removable die plate when the plunger is depressed, and an inking pad adapted to be engaged by the reversible die plate when the plunger is released.

8. In a hand stamp, the combination of a frame, a plunger slidably mounted thereon, an inking pad, a reversible die plate rotatably mounted on the plunger and adapted to normally engage the inking pad, and means for locking the plunger in its normal position.

9. In a hand stamp, the combination of a frame, a plunger slidably mounted thereon, a spring for normally retracting the plunger after said plunger has been depressed, a reversible die plate rotatably mounted on the plunger, a die plate provided with an opening through which said reversible die plate is adapted to be projected, and means for automatically locking the plunger in its normal position.

10. In a hand stamp, the combination of a frame, a plunger slidably mounted thereon, a reversible die plate rotatably mounted on the plunger, means for returning the die plate to its normal position, a die plate positioned on the outer end of the die frame and provided with an opening, the reversible die plate being adapted to be projected through the opening in the second mentioned die plate, and means for automatically locking the reversible die plate in its normal position.

11. In a hand stamp, the combination of a frame, a plunger slidably mounted relative thereto, a reversible die rotatably mounted on the plunger, a die plate provided with a die in position in advance of the reversible die, and an inking pad adapted to be normally engaged by the reversible die.

12. In a hand stamp, the combination of a frame, a plunger provided with a slot and slidably mounted relative thereto, a reversible die rotatably mounted on the plunger, and a disk pivotally and resiliently mounted on the frame and provided with an opening through which the plunger is adapted to slide, a portion of said disk being adapted to normally engage the slot in the plunger when said plunger is in elevated position.

13. In a hand stamp, the combination of a main frame, a reversible die frame rotatably

- mounted in the main frame, a plurality of dies adjustable on the reversible frame, a slotted plate for alining certain of said adjustable dies, a stud on said pivoted plate, 5 and a spring-pressed catch for automatically gripping the stud when the plate is forced into alining position with the dies.
14. In a hand stamp, the combination of a main frame, a reversible die frame rotatably 10 mounted in the main frame, a plurality of dies adjustable on the reversible frame, a slotted plate for alining certain of said adjustable dies, a stud on said pivoted plate, a spring-pressed catch for automatically 15 gripping the stud when the plate is forced into alining position with the dies, and means for automatically forcing the plate out of alinement with the dies when the catch is operated in one direction.
15. The combination with a self-inking stamp including an inking pad, a spring-actuated plunger, and a reversible die carrying printing characters, of a fixed stamp applied to the end of the frame of the self- 20 inking stamp, said fixed stamp having its printing characters facing outwardly and provided with a space or opening to allow the printing characters of the self-inking stamp to project through so that the impressions from both stamps may be simultaneously made.
16. The combination with a self-inking stamp including an inking pad, a spring-actuated plunger, and a reversible die carrying printing characters, of a fixed stamp 25 removably applied to the end of the frame of the self-inking stamp, said fixed stamp having its printing characters facing outwardly and provided with a space or opening to allow the printing characters of the self-inking stamp to project through so that the im- 30
- pressions from both stamps may be simultaneously made, one of the impressions being inclosed by the other.
17. The combination with a self-inking stamp having its frame at the bottom provided with cross bars, of a die plate carrying printing characters, means provided on the die plate to removably engage said bars and hold the die plate in fixed position with the printing characters facing outwardly, and locking means to hold the self-inking mechanism out of action so as to permit the sole use of said die plate.
18. The combination with a self-inking stamp having its frame at the bottom provided with cross bars, of a die plate carrying printing characters, means provided on the die plate to removably engage said bars and hold the die plate in fixed position with the printing characters facing outwardly, and locking means to hold the self-inking mechanism out of action so as to permit the sole use of said die plate, said die plate having an opening therein to allow the printing characters of the self-inking stamp to project through when the said locking means is released.
19. The combination with a self-inking stamp having at the bottom a fixed die plate carrying printing characters which face outwardly, and means to hold the self-inking mechanism out of action so as to permit the sole use of said die plate, said die plate having an opening therein to allow the printing characters of the self-inking stamp to project through and print in the same plane as the printing characters of the die plate, when said locking means is released.

In testimony that I claim the foregoing as my own, I have hereto affixed my signature.

ARTHUR ALBERT PANNIER.
